UNITED STATES PATENT OFFICE.

JOHN WILLIAM SCHULZE, OF PROVIDENCE, RHODE ISLAND, ASSIGNOR TO ALFRED VESTER SONS, INC., OF PROVIDENCE, RHODE ISLAND, A CORPORATION OF RHODE ISLAND.

DESIGN FOR A LEAF ORNAMENT FOR ELECTRIC FIXTURES, ETC.

Application filed January 17, 1921. Serial No. 438,028. Term of patent 3½ years.

To all whom it may concern:

Be it known that I, JOHN WILLIAM SCHULZE, a citizen of the United States, residing at Providence, in the county of Providence and State of Rhode Island, have invented a certain new, original, and ornamental Design for a Leaf Ornament for Electric Fixtures, Etc., of which the following is a specification, reference being had to the accompanying drawing, forming part thereof.

The figure is a perspective view of leaf

ornament embodying my new design which is to be used on electric fixtures though it is obvious that it may be applied to any manufacture.

I claim:

The new and ornamental design for a leaf ornament for electric fixtures, etc., as shown.

JOHN WILLIAM SCHULZE.
